UNITED STATES PATENT OFFICE

ALFRED STEINBART, OF PITTSBURGH, PENNSYLVANIA

REGULATION OF COMBUSTION OF GASES IN FURNACES

Application filed February 7, 1925. Serial No. 7,636.

When employing producer gas for heating furnaces, the combustion of coal is progressive, occurring in two stages, i. e., a preliminary combustion for the generation of gases and a complete combustion of such gases in a furnace. The air required for the complete combustion of producer gas will vary for a certain coal with the quantity of air employed for the generation of producer gas.

10 As for example, if the producer gas be generated by supplying one cubic foot of air for the partial combustion of Pittsburgh coal, the air for complete combustion of the gas in the furnace should be supplied at a rate

15 approximately equal to two cubic feet.

In the operation of producers, the rate of generation of gas is varied by varying the rate of supply of air to the producer, and the rate of supply of air for complete combustion 20 of the gas generated from a certain fuel having been determined, such relation between the air supplied to the producer and furnace, respectively, should be maintained.

The object of the invention described herein is to provide for the maintenance of a desired relation between the air supplied for preliminary combustion of coal and the air supplied for the combustion of gas generated in such preliminary combustion.

25 In the accompanying drawings forming a part of this specification, Fig. 1 is a plan view illustrating diagrammatically a form or construction of apparatus adapted to the practice of the invention described and claimed herein; Figs. 2, 3, 4, are views similar to Fig. 1 illustrating modifications of apparatus for the practice of the invention; and Fig. 5 is a sectional view on a plane indicated by the line V—V Fig. 1 and illustrates the 30 usual form of aspirator employed in supplying steam and air to a producer.

For convenience of description the air supplied for the preliminary or partial combustion of the coal and consequent formation 45 of gas will be termed "primary air" and that supplied to the furnace for the combustion of the previously formed gas will be termed "secondary air".

In practice, one or more producers 1, which 50 may be of any suitable construction, are pro-

vided with outlet pipes 2 adapted to be connected through a gas header 3 to a gas inlet valve 4 at an end of a furnace, not shown. In the construction shown in Figs. 1, 3 and 4 air is supplied to the producer and the furnace 55 by fans or blowers 5 and 5^a through mains 6 and 6^a, the former having branches 7 extending to the several producers. It is preferred that these branches be provided with valves 8, in order that a producer may be cut out when cleaning is necessary, without interfering with the operation of the other producers.

In the construction shown in Figs. 1, 3 and 4, the pumps or blowers 5, 5^a, are connected to the respective air mains 6 and 6^a, said pumps or blowers being preferably of the Root type of construction, which are adapted to deliver a predetermined volume per revolution. As shown in Fig. 1, the blowers are 65 so operatively connected to motors 9, 9^a of any suitable construction, but preferably of the steam turbine type, and the respective blowers are preferably made of such capacities that the air delivered to the producer and furnace will be in the desired relative proportions. As for example, if Pittsburgh 70 coal is being employed, the blower 5 is made of such capacity as to deliver one cubic foot of primary air to the producer while the 75 blower 5^a will have such a capacity as to deliver two cubic feet of secondary air to the furnace when driven at the same rate as the blower 5.

In lieu of proportioning the blowers in accordance with the volume of air to be delivered per revolution, the blowers may vary in capacity and be driven at such rates as to supply the desired relative volumes of air to 80 the producer and furnace.

85 While the fans may be operated by any suitable constructions of regulable motor, it is preferred as above stated to employ a steam engine such as a turbine, as the exhaust from such engine can be utilized for supplying a portion, at least, of the steam required in the generation of gas in the producers. In case 90 sufficient steam is not obtained from the exhaust, additional steam may be supplied 100

through a by-pass 10 provided with a suitable regulating valve.

The regulation of the supply of secondary air by and in accordance with the rate of flow of primary air to the producer can be attained by utilizing the differential between the drops of pressures through orifices in the conduits conducting air to the producer and the furnace, the areas of such orifices being preferably so much less than the cross sectional areas of the conduits that there will be a substantial drop in pressure of the air in passing through the orifice. In the construction shown, the fans 5 and 5^a are provided with air supply conduits 11 and 11^a, having inlet orifices 16, 16^a of areas so related to the areas of the delivery ports or outlets of the fans that the pressures in the conduits 11, 11^a will be less than atmospheric pressure. Pipes 12 and 12^a extend from the inlet pipes 11, 11^a, project up into bells 13, 13^a submerged to suitable depths in liquid contained in a tank 14. The closed upper ends of the bells are subjected to atmospheric pressure, and hence the positions of the bells will vary as the static pressures in the respective inlet pipes 11 and 11^a vary.

It is preferred in the embodiment of the improvement shown in Figs. 1 and 2, that only static pressure of the air flowing to the fans 5, 5^a should be employed for regulating purposes and to that end the conduits 11 and 11^a should be provided with stabilizing boxes 15, 15^a. These boxes are so constructed and arranged relative to the orifices 16 and 16^a, and to the points where the conduits 11 and 11^a leading to the fans are connected to the boxes that the pipes 12, 12^a may be connected to the boxes 15, 15^a at points wholly to one side of the line of flow of air through the boxes, and hence the pressure in the pipes 12 and 12^a will not be materially affected by dynamic pressure. In order that there may be a substantial or effective difference between the pressures within and without the boxes, the pressure without being atmospheric, it is preferred that the inlet ports 16 and 16^a of the boxes 15, 15^a, which will hereinafter be termed orifices, should have areas about one-half of the areas of the inlet ports of the fans. The proportion of the areas of the orifices 16 and 16^a should be made, however, the same as the proportions of primary and secondary air desired for the coal gasified, for instance, one to two for Pittsburgh coal. The pipes 12, 12^a leading to the bells 13, 13^a, are connected to the stabilizing box.

The bells 13, 13^a are suspended from opposite ends of a lever 17 which is adapted to control a motor indicated at 18 which through a cord 19 or other suitable means is operatively connected to a valve 20 in the steam pipe leading to the turbine 9^a.

In the operation of the described apparatus the fan 5 will be regulated by the manipu-

lation of the valve in the steam supply pipe of the turbine 9 until the required quantity of air is supplied to the producers. By the operation of the fan 5, the static pressure in the box 15 and under the bell 13 will be reduced or drop below atmospheric pressure and the bell will move down, thereby causing such a movement of the motor 18 as to open the valve 20 causing the operation of the fan 5^a. The speed of the fan 5^a will increase until the drop of pressure through the orifice 16^a will be substantially the same as the drop of pressure through the orifice 16, and the bells 13 and 13^a will have moved to normal position, thereby checking any further opening of the valve 20. If at any time it is desirable to vary the rate of supply of primary air in order to vary the supply of gas to the furnace, the fan 5 is accelerated or retarded, thereby changing the static pressure of air in the stabilizing box 15, and the bell 13, which will then move up or down shifting the valve 20 to vary the rate of rotation of the fan 5^a. This change in the speed of the fan 5^a will bring about a change in the drop of pressure through the orifice 16^a until such drop of pressure is equal to that through the orifice 16. The rate of supply of primary air may also be changed by opening or closing the valve A in the conduit connecting the producer with the furnace. The closure of the valve would, if a fan or aspirator were employed for supplying primary air, prevent the flow of air to the producer and there would not be any drop of pressure through the orifice 16 of the stabilizing box 15.

As shown in Figs. 2 and 5, the primary air may be supplied to the producers 1 by means of aspirators 21 of any suitable construction arranged in the branches 7 connecting the air main 6 with the producers. In such cases the stabilizing box 15 is arranged at the inlet end of the air main 6 and a pipe 12 extends from such box to a bell in the regulating mechanism.

In Fig. 3 is shown a construction wherein provision is made for effecting regulation by and in accordance with the rate of flow of primary air to the delivery side of the fan 5, substantially such as is described. As shown in Fig. 3, bells each having two compartments 22, 22^a; 23, 23^a, are submerged to a suitable depth in a tank 24 and from the main 6 for the primary air, pipes 26 and 26^a extend to the tank and are projected up into the chamber 22 of one bell and the chamber 22^a of the other bell.

The pipes 26, 26^a, are so connected to the main 6 that static pressure of the air will be exerted in the compartment 22^a of one bell and static pressure plus dynamic pressure will be exerted in the compartment 22 of the other bell, and the pipes 27, 27^a, are so connected to the air main 6^a leading to the furnace that the static pressure of the air flow-

ing therein will be exerted in the compartment 23, and the static plus the dynamic pressure in the main will be exerted in the compartment 23^a. These bells are suspended from a lever 17 adapted to control the operation of a motor 18 operatively connected to a valve 20 controlling the flow of steam to the turbine 9^a operating the fan 5^a supplying the secondary air.

10 In lieu of controlling the supply of secondary air to the furnace by and in accordance with changes in the quantity of primary air supplied to the producers, the operation of the apparatus may be reversed as shown in Fig. 4. As shown therein, a hand operated valve 26^a is employed for controlling the motor 9^a operating the fan 5^a which supplies secondary air to the furnace and the motor 18 is connected by a cord 19^a to a lever or other 20 device adapted to shift the valve 20^a controlling the supply of steam to the turbine 9 which operates the fan 5 supplying primary air to the producers.

For purposes of illustration, reference has been made herein to the relative proportions of primary and secondary air required when Pittsburgh coal is employed for the heating of a furnace. The proportions of primary and secondary air, when Pennsylvania coal is charged into the producer, are in proportion of approximately one to two. It should be understood, however, that if the producer gas is formed by a partial combustion of coke in the producer, then the relative proportions of primary and secondary air will be more than in the previous statement, as there will be no volatile constituents to be burned.

Also, it should be understood that the rate of production of producer gas will vary not only as between coal and coke but also as between coals from different fields, wherein the volatile constituents vary from that of the Pittsburgh coal.

45 I claim herein as my invention:

1. The method herein described for effecting the progressive combustion of coal which consists in effecting a preliminary combustion of coal, supplying air for such preliminary combustion in quantities less than that required for complete combustion of the coal, effecting the combination of the gas formed during the preliminary combustion and regulating the supply of air for one of such combustion stages by and in accordance with the air supplied for the other combustion stage.

2. The method herein described for the combustion of coal which consists in the formation of a gas by the partial combustion of the coal, effecting the combustion of such gas in a furnace and regulating the supply of air for the combustion of the gas in the furnace by and in accordance with the air

supplied in effecting the partial combustion of the coal.

3. The method herein described for effecting the progressive combustion of coal, coke, etc., which consists in effecting a preliminary combustion of the coal, supplying air for such preliminary combustion in quantities less than that required for complete combustion of the coal, effecting the combustion of the gas formed during the preliminary combustion and regulating the air supplied for the combustion of the gas by and in accordance with the quantity of air supplied for the preliminary combustion.

4. An apparatus for the combustion of coal, coke, etc., for heating a furnace having in combination a furnace, a producer for supplying gas to the furnace, means for supplying air to the producer for the generation of gas, means for supplying air to the furnace for the combustion of the gas and regulating means responsive to variations in the supply of air to the producer for proportionately and simultaneously varying the supply of air to the furnace.

5. The method herein described for the combustion of coal, coke, etc., which consists in the formation of producer gas, effecting the combustion of such gas and regulating the air supplied for such combustion by and in accordance with the quantity of air supplied for the formation of producer gas.

6. An apparatus for the combustion of coal, coke, etc., for heating a furnace, having in combination a furnace, a producer for supplying gas to the furnace, means for supplying air to the producer, means for supplying air to the furnace for the combustion of the gas, and regulating means responsive to variations in the supply of the air to the producer for varying the supply of air for combustion in the furnace, proportionately to the rate of generation of gas in the producer.

7. An apparatus for the combustion of coal, coke, etc., the combination of a furnace, a producer connected to the furnace, means for supplying primary air to the producer, comprising means for effecting a drop of pressure in the primary air at a suitable point in the line of flow of such air to the producer, means for supplying secondary air to the furnace for the combustion of the gas supplied by the producer, and means operative by and in accordance with the drop of pressure in the primary air for controlling the supply of secondary air flowing to the furnace.

8. A plant having in combination a furnace, a producer for supplying gas to the furnace, means for supplying primary and secondary air to the producer and furnace, respectively, comprising means for effecting drops of pressure at suitable points in the lines of flow of the primary and secondary air, means whereby the pressures at said points are differentially opposed, and means

operative by the difference in pressure drops for controlling the flow of secondary air to the furnace.

9. A plant having in combination a furnace, a producer for supplying gas to the furnace, means for supplying primary and secondary air to the producer and the furnace, respectively, and means for controlling the secondary air supplied to the furnace in accordance with the air supplied to the producer comprising a regulator responsive to differential pressures and duct means connecting the supplies of primary and secondary air, respectively, to said regulator.

10. A plant having in combination a furnace, a producer for supplying gas to the furnace, means for supplying primary and secondary air to the producer and furnace, respectively, means responsive to the differentials of dynamic and static pressures between suitable points in the line of flow of the primary and secondary air, respectively, for controlling the secondary air to the furnace.

11. A plant having in combination a furnace, a producer for supplying gas to the furnace, means comprising fans for supplying primary and secondary air to the producer and furnace, respectively, means responsive to the relative pressures at suitable points in the lines of flow of the primary and secondary air, respectively, for controlling the speed of the fan supplying air to the furnace.

12. A plant having in combination, a furnace, a producer for supplying gas to the furnace, means for supplying primary and secondary air to the producer and furnace, respectively, said means providing an excess in one of said air supplies, and means responsive to changes in the relative pressures in said air supplies, respectively, for regulating the flow from said excess supply.

13. A plant having in combination a furnace, a producer for supplying gas to the furnace, means for supplying primary and secondary air to the producer and furnace, respectively, said means providing an excess in one of said air supplies, and means responsive to variations in the relative quantities of primary and secondary air supplied for regulating the flow from said excess supply.

14. A plant having in combination a furnace, a producer for supplying gas to the furnace, means for supplying primary and secondary air to the producer and furnace, respectively, said means providing an excess in one of said air supplies, and means for regulating the flow from said excess supply comprising a regulator connected by flow ducts with said respective supplies.

60 In testimony whereof, I have hereunto set my hand.

ALFRED STEINBART.

CERTIFICATE OF CORRECTION.

Patent No. 1,751,894.

Granted March 25, 1930, to

ALFRED STEINBART.

It is hereby certified that error appears in the printed specification of the above numbered patent requiring correction as follows: Page 3, line 52, claim 1, for the word "combination" read "combustion"; and that the said Letters Patent should be read with this correction therein that the same may conform to the record of the case in the Patent Office.

Signed and sealed this 24th day of June, A. D. 1930.
